UNITED STATES PATENT OFFICE

CHARLES J. AULBACH, OF PASSAIC, NEW JERSEY, ASSIGNOR TO CONTINENTAL CAN COMPANY, INC., OF NEW YORK, N. Y., A CORPORATION OF NEW YORK

MECHANISM FOR CURLING THE EDGES OF IRREGULAR-SHAPED CONTAINERS

Application filed November 28, 1928. Serial No. 322,507.

The invention relates to new and useful improvements in a mechanism for curling the edge of an irregular shaped container, and is particularly adapted for curling the 5 edge of the container body to clamp and secure an inner sealing member to the container.

An object of the invention is to provide a curling mechanism wherein the edge is 10 curled by means of a curling die, which is provided with devices for holding the metal wall of the container in proper engagement with the die to insure the forming of an uniform curl at the edge of the container 15 all the way around the same.

A further object of the invention is to provide a mechanism of the above character with devices cooperating therewith for placing and securing an inner sealing member 20 to a container of the above type.

A still further object of the invention is to provide a mechanism of the above character wherein the inner seal is held firmly against the side and end walls of the container, and the walls of the container in 25 turn held in proper relation to the die for producing a uniform curl which is pressed against and grips the inner seal for securing the same to the container.

These and other objects will in part be 30 obvious and will in part be hereinafter more fully described.

In the drawings:—

Figure 1 is a view partly in section and 35 partly in front elevation showing a can seal attaching device embodying the improvements.

Fig. 2 is an enlarged view in section of the seal attaching head, said section being 40 taken in the same plane as the section in Fig. 1.

Fig. 3 is a view similar to Fig. 2, showing the head as raised.

Fig. 4 is a sectional view on the line 4—4 45 of Fig. 2.

Fig. 5 is an enlarged section through a portion of the head showing the can and sealing member placed, and with the chuck or outer protecting member brought into 50 engagement with the sealing member.

Fig. 6 is a view similar to Fig. 2, but showing the head moved downward so that the edge of the can is rolled inwardly and outwardly into gripping contact with the flange of the sealing member. 55

Fig. 7 is a detail showing the position of the die and the member for holding the wall of the container against the die at the beginning of the curling action.

Fig. 8 is a similar view showing the completion of the curl. 60

The invention is directed broadly to a mechanism for curling the edge of an irregular shape container, and is adapted particularly for curling the edge in order to 65 cause the edge to engage and firmly clamp an inner paper seal.

In my prior Patent No. 1,630,687, granted May 31, 1927, there is shown and described an inner non-metallic sealing member having a flange extending along the body wall of a container, which sealing member is secured to the container, which sealing member is secured to the container by curling the metal of the container inwardly, downwardly and outwardly into gripping contact with the flange of the sealing member. The container is cylindrical, and the curling of the edge may be readily accomplished by a curling roll, or other equivalent mechanism. 70 75 80

The present invention has to do with a mechanism for die curling the edge of an irregular shaped container, and as stated for the particular purpose of securing an inner sealing member. The die curling head includes a die which is shaped to conform to the edge of the container. This head has a movement relative to the container and when said head moves into contact with the metal of the container it will roll the edge into a curl, often referred to as a false wire. The rounded corners of the container will remain in proper position relative to the curling die, but the straight side and end walls between the rounded corners are liable to get out of proper alinement, and therefore the die curling mechanism is provided with means which engages these walls between the rounded corners and holds the 85 90 95 100

walls of the container firmly against the walls of the curling die so as to insure that the curling die will properly engage the container and produce a uniform curl extending all the way around the edge of the container. These devices which hold the walls of the container against the wall of the die are carried by the die curling head, and are actuated thereby. When the device is used for attaching an inner sealing member to a container, this inner sealing member is placed within the container body and properly supported adjacent the end where the curl is to be formed. The sealing member is provided with a vertical flange, which contacts with the inner faces of the walls of the container. The device which holds the container wall against the die also holds the flange of the sealing member against the walls of the container, and thus it is that the sealing member is properly positioned relative to the container body so that when the edge is curled it will be turned inwardly, downwardly and outwardly into gripping contact with the flange of the sealing member.

Referring more in detail to the drawings, the mechanism for curling the edge of the container body includes a support 1 on which the container body 2 is placed. This support has a cross sectional shape corresponding to that of the container body, and the container body fits loosely on this support. The container body projects above the support as clearly shown in the drawings. Inasmuch as my curling mechanism is particularly adapted for attaching an inner sealing member to a container, I will describe in detail the manner of using the curling mechanism for this purpose.

The inner sealing member is shown at 3 in the drawings. This inner sealing member is provided with a flange 4. The inner sealing member is placed on top of the support 1. The inner sealing member may be made of paper or any other fragile material, but is preferably non-metallic so that when the container is first opened the inner sealing member may be broken and removed and an outer sealing member used for reclosing purposes.

The head for attaching the sealing member to the container is carried by a supporting frame 5. This supporting frame 5 may be attached to a table and on the same table means provided for forming the sealing member and inserting the same in the container body and on the support 1, in which case the support 1 will travel from one station to the other.

The frame 5 is provided with suitable guideways 6 in which a head 7 is adapted to move up and down. The head is raised and lowered by means of a link 8 cooperating with a crank carried by a main shaft

mounted in the housing 9 at the upper end of the frame 5. This main shaft may be driven by a suitable sprocket chain 10, or in any other suitable way. As the shaft rotates the crank will raise and lower the link and the link will raise and lower the head. The head is provided at its upper end with spaced lugs 11, 11, and the lower end of the link extends between these lugs and is pivotally secured thereto by a pivot pin 12.

The attaching head 7 carries a depending extension 13 which is rigidly secured to the head 7. A sleeve 14 is located centrally of the head and has a threaded connection with a stem 15 secured by means of a clamping nut 16 to the extension 13. This sleeve is provided with an inner shoulder 17 and freely movable in the sleeve is a rod 18 having an enlarged head 19 adapted to engage the shoulder 17. This rod 18 carries at its lower end a chuck 20. A spring 21 normally presses the chuck downwardly and its downward movement is limited by the head 19 engaging the shoulder 17. This chuck is for the purpose of engaging the inner sealing member resting on the support for protecting the same during the attaching of the sealing member to the container. The container, as shown in the drawings, is an oblong container, rectangular in cross section with rounded corners. The chuck is made to conform to the cross section of the container and is of such dimensions that it may be readily removed from contact with the sealing member past the curled edge which secures the sealing member to the container, after said container edge has been curled for this purpose.

Mounted on the extension of the attaching head are four holding jaws which, except for length, are all similar. These jaws are indicated at 22 in the drawings. Each jaw is pivoted at 23 to a bracket 24 carried by a rod 25 mounted for free movement vertically in the extension 13. At the upper end of this rod there is a plate 26 which is adapted to engage a shoulder at the bottom of the recess 27. A spring 28 surrounds the rod and bears against the bracket at its lower end, while the upper end of this spring seats in a recess in the extension 13 of the attaching head. These springs normally tend to force the rods 25 downwardly and thus force the jaws downwardly on the attaching head.

Each jaw is provided with a cam shoulder 29 which is adapted to cooperate with a cam face 30 in the extreme lower end of the sleeve 14. Each jaw also has a straight portion 31 extending downwardly from this cam shoulder 29. Each jaw is provided with a recess 32. A coil spring 33 encircles all of the jaws and lies in these recesses 32. This coil spring tends to move the lower ends of the jaws inwardly toward the center of the head

and this inward movement of the jaws is limited by the cam face 30 and the outer wall of the sleeve directly above the same.

At the lower end of the extension 13 of the attaching head there is a curling die 34. This curling die 34 is provided with a vertical wall 35 which leads to a curling recess 36 at its upper end. The extreme upper edge of the container body is curved inwardly slightly as indicated at 37, while the extreme lower end of the vertical wall 35 is curved outwardly slightly. When this curling die moves downward onto the container body, the edge of the container body will pass along the wall 35 and into the curling recess 36. This curling recess extends all the way around the container body and conforms to the shape of the container body so that the edge of the container body will be curled inwardly uniformly all the way around.

When the head is in its extreme upper position the support with the container body placed thereon and the sealing member in place on the support is placed beneath the head. As the head moves downwardly the chuck 20 first comes into engagement with the sealing member and the spring 21 will then be compressed, thus yieldingly holding the chuck pressed against the sealing member.

As the head continues its downward movement, the jaws 22 will be caused to contact with the upper face of the chuck. The extreme lower ends of these jaws are curved about the pivotal support of the jaws as a center, and the upper face of the chuck is inclined so that the jaws may contact with the chuck and freely slide outwardly into gripping engagement with the flange of the sealing member. After the jaws make contact with the chuck, a further downward movement of the jaws is restrained and the springs 28 will be compressed allowing the supporting rods 25 to move upwardly into the extension 13. The sleeve 14, however, continues its downward movement, and therefore, the cam face 30 sliding along the cam shoulder 29 will positively force these jaws outwardly, all jaws simultaneously moving outwardly until the ends 38 engage the vertical wall of the flange 4. This will hold the vertical flange 4 snugly in engagement with the inner wall of the container body. Inasmuch as these jaws move inwardly toward the center of the head, they are necessarily limited somewhat as to length so as to permit this free inward movement. There is, however, a sufficient length to the jaws to hold the flange of the sealing member snugly against the wall of the container body. As the head continues its downward movement, the vertical wall of the sleeve 30 will pass along the straight wall on the jaws directly beneath the shoul-

der 29 and thus hold the jaws in their outer clamping position as clearly shown in Fig. 6 of the drawings. This further movement of the head in a downward direction brings the curling die into engagement with the wall of the container body and will roll said wall inwardly and outwardly, as indicated at 39 in Figs. 1, 2 and 6, until it is brought into gripping contact with the vertical flange of the sealing member.

As the head moves upwardly the curling die will first be released from engagement with the container, after which the jaws will be released by the sleeve and the coil spring will at once retract the jaws moving the ends of the jaws from beneath the curled edge of the container body. During this upward movement of the jaws, there is no bodily vertical movement of the jaws. The springs 28 will hold the jaws in contact with the chuck until the head has risen to a point where the bracket 24 engages the upper face of the curling die. When these brackets come into contact with the die or the plate 26 limits the downward movement of the rods 28 then the jaws will be raised vertically with the head and retracted from contact with the chuck. The chuck will also be lifted from contact with the sealing member and all of the parts will continue their upward movement with the rising movement of the attaching head.

As has already been stated, my improved die curling mechanism may be used for curling the edge of an irregular shaped container for producing a false wire without attaching any inner sealing member thereto. In Figs. 7 and 8 I have shown a curling die as used for curling the edge of the container body without attaching any inner seal. The jaws 22 have the same movement as when attaching the inner seal. These jaws are adjusted so that if they are brought into contact with the side and end walls respectively of the container body and will hold these walls up against the entering wall of the die, which is indicated at 35 in the drawings. As noted, the die is shaped to conform to the normal outlines of the container body, and the rounded corners will remain in proper position so as to engage the die in such a way as to be properly curled. It is the side and end walls between the rounded corners which are likely to be misshaped or bent so as to not lie properly against the entering wall of the die. These jaws will force the side and end walls between the rounded corners into firm contact with the entering wall of the curling die and thus the curling recess 36 will properly contact with the edge of the container so as to curl the same inwardly, downwardly and outwardly thus forming a false wire and a finish for the outer edge of the container body.

While I have described the principal use of my curling mechanism for securing an inner sealing member to the container, it will be understood, in view of the description just given, that this curling mechanism may be used for other purposes without departing from the spirit of the invention as set forth in the claims.

From the above it will be apparent that 10 a mechanism has been provided for die curling the edge of an irregular shaped container where all the parts are operated through a single eccentric member which raises and lowers the die curling head. It

15 will be understood, however, that the manner of actuating the parts and raising and lowering the head may also be greatly varied without departing from the spirit of the invention as set forth in the claims.

20 While the chuck protects the sealing member when the curling mechanism is used, and also cooperates with the jaws in permitting free movement of the jaws into clamping engagement with the flange of the 25 sealing member, it will be understood that from certain aspects of the invention this chuck may be omitted and the jaws limited in their downward movement by the support for the container.

30 It is obvious that minor changes in the details of construction and the arrangement of the parts may be made without departing from the spirit of the invention as set forth in the appended claims.

35 Having thus fully described my invention, what I claim as new and desire to secure by Letters Patent, is:—

1. A mechanism for die curling the edge 40 of an irregular shaped container, comprising a reciprocating head, a die carried by said head for engaging the walls of the container body for curling the same, and means carried by said head for holding the walls of the container against the entering walls 45 of the die as the container passes into said die for insuring a uniform curl.

2. A mechanism for die curling the edge 50 of an irregular shaped container, comprising a reciprocating head, a die carried by said head for engaging the walls of the container body for curling the same, jaws mounted on the head for bodily vertical movement and for independent oscillation, and means associated with the jaws for moving the same so as to cause said jaws to engage the side and end walls of the container for holding said walls against the entering walls of the die as the container passes into said die for insuring a uniform curl.

3. A mechanism for die curling the edge 55 of an irregular shaped container, comprising a reciprocating head, a die for engaging the walls of the container body for curling the same, a plurality of independent jaws

mounted on the head for bodily vertical movement, a cam carried by the head for engaging the jaws, springs for moving the jaws bodily away from the cam, yielding means for moving the jaws radially toward the center of the head when released by the cam, and means for moving the head relative to the jaws for causing the jaws to engage the end and side walls of the container body for holding said walls against the entering walls of the die as the container passes into said die for insuring a uniform curl.

4. A device for attaching an inner sealing member to a container body including means for supporting a container, means within the container body for supporting a sealing member having a flange with said flange extending outwardly along the body wall of the container, means for engaging the flange of the sealing member for holding the same against the wall of the container, and a die curling means for engaging the wall of the container body for curling the same inwardly and outwardly into gripping contact with the flange of the sealing member.

5. A device for attaching an inner sealing member to a container body including means for supporting a container, means within the container body for supporting a sealing member having a flange with said flange extending outwardly along the body wall of the container, movable clamping jaws for engaging the flange of the sealing member for holding the same against the wall of the container, and a die curling means for engaging the wall of the container body for curling the same inwardly and outwardly into gripping contact with the flange of the sealing member.

6. A device for attaching an inner sealing member to a container including means for supporting a container and a sealing member having a flange, with said flange extending outwardly along the body wall of the container, a reciprocating head, movable jaws carried by said head, means associated with the jaws for moving said jaws outwardly into contact with the flange of the sealing member for holding the same against the wall of the container, and a die curling means carried by said head for subsequently engaging the wall of the container body for curling the same inwardly and outwardly into gripping contact with the flange of the sealing member.

7. A device for attaching an inner sealing member to a container including means for supporting a container and a sealing member having a flange, with said flange extending outwardly along the body wall of the container, a reciprocating head, pivoted jaws mounted on said head for bodily vertical movement and for independent oscillating, means associated with the jaws for moving

said jaws for oscillating the jaws so as to cause the same to engage the flange of the sealing member for holding said flange against the wall of the container, and a die 5 curling means for engaging the wall of the container body for curling the same inwardly and outwardly into gripping contact with the flange of the sealing member.

8. A device for attaching an inner sealing member to a container including means for supporting a container and a sealing member having a flange, with said flange extending outwardly along the body wall of the container, a reciprocating head, a plurality of 15 independent jaws mounted on said head for bodily vertical movement, a cam carried by the head for engaging the jaws, springs for moving said jaws bodily away from the cam, yielding means for moving the jaws radially 20 toward the center of the head when released by the cam, said support for the sealing member serving as a means for limiting the downward movement of the jaws when the head is moved downward, whereby said cam 25 forces the jaws into engagement with the flange of the sealing member, and a die curling means carried by the head for engaging the wall of the container body for curling the same inwardly and outwardly into gripping contact with the flange of the sealing member.

9. A device for attaching an inner sealing member to a container including means for supporting a container and a sealing member 35 having a flange, with said flange extending outwardly along the body wall of the container, a reciprocating head, a plurality of independent jaws mounted on said head for bodily vertical movement, a cam carried 40 by the head for engaging the jaws, springs for moving said jaws bodily away from the cam, yielding means for moving the jaws radially toward the center of the head where released by the cam, a yielding chuck carried 45 by said head adapted to engage the sealing member on the supporting means therefor, said chuck operating to limit the downward movement of the jaws, whereby said cam will force the jaws outwardly into engagement with the flange of the sealing member, and a die curling means carried by said head 50 for engaging the wall of the container body for curling the same inwardly and outwardly into gripping contact with the flange of the sealing member.

In testimony whereof, I affix my signature.

CHARLES J. AULBACH.
